J. M. CALLOW.
FLOTATION SEPARATORY APPARATUS.
APPLICATION FILED APR. 27, 1914.

1,366,767.

Patented Jan. 25, 1921.

UNITED STATES PATENT OFFICE.

JOHN M. CALLOW, OF SALT LAKE CITY, UTAH, ASSIGNOR, BY MESNE ASSIGNMENTS, TO PNEUMATIC PROCESS FLOTATION COMPANY, OF NEW YORK, N. Y., A CORPORATION OF DELAWARE.

FLOTATION SEPARATORY PROCESS AND APPARATUS.

1,366,767.

Specification of Letters Patent. Patented Jan. 25, 1921.

Application filed April 27, 1914. Serial No. 834,768.

To all whom it may concern:

Be it known that I, JOHN M. CALLOW, a subject of the King of Great Britain, residing at Salt Lake City, in the county of Salt Lake and State of Utah, have invented certain new and useful Improvements in Flotation Separatory Processes and Apparatus, of which the following is a specification.

My invention relates to a flotation separatory process and apparatus designed for the concentration of metallic ores by separating the metallic particles from the barren or rocky constituents thereof, and the invention consists of the parts, constructions, arrangements and combinations of parts and the separatory process which I will hereinafter fully describe and claim.

In the accompanying drawing forming a part of this specification and in which similar reference characters indicate like parts in the several views;

Figure 1 is a vertical sectional view with parts in elevation, of a flotation or separatory apparatus embodying the salient features of my invention.

Fig. 2 is a horizontal sectional view of a part of the apparatus on the line X—X of Fig. 1.

Fig. 3 is a modification to be referred to. Fig. 4 is a sectional detail of a swiveled connection, 28.

The apparatus shown in the present case is specifically related to the art commonly known as buoyant processes and which is distinct from the usual amalgamation processes in which the ore forms an amalgam, in that in the buoyant processes a certain percentage of oil, or of two dissimilar oils, or an oil and an acid, or an oil and an alkali is mixed with finely ground ore pulp and the mixture is then subjected to a violent agitation with the result that large volumes of air are beaten into and entrained by the pulp for the purpose of producing a froth composed of bubbles of air and oil to which the mineral particles attach, said froth having the appearance of an aggregation or mass of fine soap bubbles which when collected and the froth discharged or broken down, by natural settlement, or by the addition of cold water, or other means, displaces the mineral particles that have been caught.

In another application filed by me on the 1st day of April, 1914, Serial Number

828,805, I have disclosed and claimed what I term a separatory tank of substantially rectangular form having a bottom portion inclined and provided with a series of independent cells adapted to contain air, gas or vapor under pressure, and a porous wall or upper surface forming the top of the cell and through which the air, gas or vapor is delivered into the solution, or the mineral bearing pulp in innumerable fine streams distributed irregularly substantially throughout the entire area of the pulp.

In another application filed by me on the 6th day of July, 1914, Serial Number 831,050, I have fully described and claimed a process for removing by vacuum or suction, the froth, foam or suds, which accumulates on the surface of the pulp, and thereby breaks down the bubbles to displace the mineral particles which they have caught during the ascent of the bubbles through the body of pulp which mineral particles, together with any liquid matter that might come under the action of the vacuum or suction, being separated from the main body of the pulp and delivered into a vacuum tank or vessel wherein the solids are precipitated or settled and from which they may be withdrawn as a concentrate.

The present invention is related distinctly to the two inventions above mentioned for which applications for patents have been made, and it discloses another type of apparatus by which the aforesaid vacuum process may be carried out.

In the present instance, the tank, A, may be of any suitable construction and capacity. Preferably, it is of circular form and has double walls, 10—10', forming between them an annular space, 11, into which the pulp to be treated is first admitted, the inner wall, 10', being shorter than the outer wall and terminating above the bottom of the tank so as to form a space through which the pulp may flow into the chamber of the tank from below.

The tank has an appropriate bottom which at its center is provided with a hub or bearing, 12, which is connected with a tailings discharge pipe, 13.

To the bottom of the tank are fixed in any desired manner a series of vertical partitions, 14, which stand on edge and may have a uniform or variable height. In Fig. 1 I

show these partitions and which in this figure are supposed to be of circular form, of different heights, the height of the partitions increasing from the center of the tank 5 outwardly and the upper ends of the partitions forming a suitable support for a false bottom or floor, 15. This bottom, or floor, combined with the partitions forms a series 10 of independent cells in the bottom of the tank and the false bottom forms the top of said cells and is formed of some appropriate porous medium; porous brick, or a layer of fine sand between two restraining layers of screen cloth, or layers of fibrous material laid one above the other, such as cocoa 15 matting, or porous wood, as bass-wood, or one or more layers of any suitable fibrous material, as canvas or filtering cloth, capable of subdividing air, gas or vapor into more 20 or less irregular jets of infinite number and fineness may be used and are within the scope of my invention and which porous materials are fully described and claimed in 25 conjunction with other features in my pending applications Serial Numbers 793,693, filed October 6, 1913, and 806,361, filed December 13, 1913.

It will be observed that by reason of the 30 variable heights of the partitions, 14, the porous material, 15, forming the false bottom, or floor, slopes downwardly from the inner circumference of the tank to the central hub-portion, 12, and thus communicates 35 at the latter point with the tailings discharge pipe, 13. The purpose of thus declining the porous material from all sides to a common point will be readily understood from the following:

40 Material, admitted into the annular space, 11, of the tank passes under the lower edge of the inner wall, 10', of said tank and onto the higher part of the porous medium, and the pulp flows down the inclined surface of 45 said medium and gradually fills the tank to the proper level. As the pulp flows down the inclined surface of the porous medium during the filling operation, the coarser particles of material, say the coarse sands, too 50 heavy to be lifted by the pressure of air, gas or vapor emitted through the porous medium will naturally gravitate down the incline from all directions toward the lowest point or center and into the tailings discharge, 13.

55 Experiments conducted by me have shown that if the coarse sands are permitted to accumulate on the top surface of the porous medium, they would soon blanket the latter 60 and to a great extent render this medium ineffective for the best results. So long as the slime was infinitely fine and slimy, the air, gas or vapor pressure was ample and the velocities maintained in the tank were 65 sufficient to discharge everything over the

discharge lip or edge of the tank provided for that purpose, but when treating comparatively coarse and sandy material, the air pressures and velocities were found to be too low to raise the coarse sands over into 70 the launder so that they might be discharged; accordingly, they would gradually accumulate to such an extent as to form a layer or blanket of sand above the porous medium and so retard or prevent the free 75 passage therethrough of the air, gas or vapor used for aerating and agitating the pulp, and the air, gas or vapor instead of being distributed over the entire surface of the pulp, would all come up through some 80 small area which might represent a path of least resistance and so destroy to some extent the action of the air, gas or vapor. To meet this objection I found it desirable 85 to incline the porous medium so as to cause the heavier particles or coarse sands to gravitate over the surface of the medium to a discharge point rather than tending to lodge upon and finally blanketing the porous medium; and with this object in view 90 and applying the results of the former experiments to the present type of apparatus, it will be apparent that if during the agitation and aeration of the pulp by the fine streams of air, gas or vapor, delivered through the porous medium, there is any 95 tendency of the coarse sands or other material to settle upon said medium, the velocity of the air, gas or vapor is sufficient to give a slight movement to the particles and this movement, plus the more or less steeply inclined floor formed by the upper surface of the porous medium, will result in these 100 coarse particles being maintained under 105 movement and gravitating to the lower end or central point of the tank and into the tailings discharge pipe, 13.

As the sands removed from one portion of the porous medium gravitate over the surface they come into contact with the sands which have lodged or tend to lodge upon the lower portions of the porous medium and this gives movement to these sands so that in the aggregate the coarser sands are 110 caused to be automatically removed and the surface of the filter medium to be kept substantially clean for the free discharge of the air, gas or vapor, and, therefore, there is no possibility of the fine slimes settling upon 115 and forming a blanket for said porous medium.

Compressed air, or a gas or vapor under pressure is supplied to the various cells formed in the bottom of the tank through a 125 valve-controlled pipe, 55, having valve-controlled branches, 56, one of which leads to each of the aforesaid cells, the volume of air, gas or vapor admitted into each compartment being, preferably, under pressure 130

substantially equal to the hydraulic head of that portion of the pulp immediately above the particular cell.

While I prefer, for reasons above stated, 5 that the porous medium shall be inclined to effect the automatic discharge of the coarse sands, I do not limit the novel features of my invention to this arrangement and, accordingly, in Fig. 3, I show the porous medium, 16', as being horizontal throughout its length as I regard this change as within the scope of my invention. In either case 10 the several cells are designed as receivers for air, gas or vapor, under pressure, and 15 this air, gas or vapor is emitted through the porous medium in the form of innumerable fine streams or jets, this being for the purpose of both aerating and agitating the pulp immediately above the several compartments, 20 the compressed air, gas or vapor becoming the medium of (1) aerating or charging the pulp with a desired volume of air, gas or vapor and (2) it likewise induces and maintains an agitation or ebullition of 25 the pulp and the oily constituents thereof and produces a froth composed of bubbles of air, having an envelop or covering of oily matter to which the mineral particles in the pulp have an affinity and will attach.

30 To further assist in maintaining the upper surface of the porous medium substantially clean of any material which would tend to blanket or clog the pores thereof, I have shown suitable arms, 17, radiating from a central hub, or collar, 18, and which arms are preferably formed of piping and are designed to act as revolving stirrers. These arms are arranged a short distance above the surface of the porous medium and are 35 inclined to conform thereto and they operate with a sort of sweeping action to further agitate and start in motion those coarse sands which would tend to lodge upon and clog said medium.

40 The collar, 18, to which the arms are secured, is fixed to the lower end of a vertical rotatable shaft, 19, and the arms are suitably braced by rods, 20, connecting the central portions of the arms with the shaft 45 at a point above the aforesaid collar.

The shaft, 19, is mounted in suitable bearings, 21, and the upper part of the shaft is of tubular form for a purpose I will herein-after mention.

50 There is also secured to the shaft, the smaller end of a cone, 22, and this cone is provided with horizontally extending wings or vanes, 22', which are designed to operate in the body of pulp to induce a rotation or circular movement thereof during the period that the air, gas or vapor is being discharged into the pulp from below.

The purpose of the cone, 22, is to form an upwardly inclined wall for directing 55 the constantly forming bubbles upwardly

and outwardly and within the range of action of the vacuum devices, which are designed to break down these bubbles and remove adhering mineral particles to a suitable tank, where the concentrates may be 70 separated and discharged.

It will be well understood in this art that the bubbles are in the form of a froth, foam or suds, and that they accumulate upon the surface of the pulp. In order to remove 75 this froth as it forms, I locate within the tank any desired number of suitable vacuum nozzles, 23, whose open ends are presented downwardly toward the mass of accumulating froth, foam or suds, said nozzles 80 being sufficiently long as to practically extend completely across the space between the inner wall, 10, of the tank and the upper or larger end of the cone, and beneath which nozzles the inclined wall of the cone is 85 adapted to direct the foam as it forms.

The vacuum nozzles are connected with hollow arms, 24, which in turn are rigid with a sleeve, 25, which embraces the hollow shaft, 26, which is arranged in line with 90 and is practically a continuation of the shaft, 19, to which the lower end of the shaft, 26, is secured, in any appropriate manner.

The inner ends of the hollow arms, 24, 95 are open or provided with ports which are designed to register with other ports, 27, formed in the lower part of the hollow shaft, 26, when relative movement is imparted to the shaft and arms, said shaft, 26, having 100 its upper end connected by an air-tight swiveled connection, 28, of any appropriate character, for instance, as shown in Fig. 4, to a pipe, 29, the opposite end of which leads into a tank, 30, and which tank is 105 connected with the inlet end of an exhaust fan, 31, or like device for creating and maintaining a vacuum in said tank, the tank being provided with a vertical partition, 31, to prevent the short circuiting of the air 110 current induced in the pipe, 29, and insuring a delivery into the vacuum tank of the metallic particles and any solution picked up by the vacuum nozzles. In this tank the solid matters are allowed to precipitate 115 and to be discharged through a valve-controlled outlet in the bottom, which discharge may be continuous or intermittent, as may be desired.

Connected to the hollow shaft, 26, is suitable gearing, 32, which may be of any desired character, for rotating the shaft; and surrounding said shaft is a hopper or receiver, 33, into which leads a spout, 34, for conducting the material into the hopper, said 120 hopper having extending downwardly at an incline from it, the feed distributing pipes, 35, the lower ends of which lead into the annular space, 11, between the double walls of the main tank, A. 125

The tank, A, is extended at one end to form a housing, 36, the lower part of which opens into the annular space, 11, said housing forming a chamber in which operates a float, 37, on the end of a pivoted lever, 38, one arm of which is connected to a rod, 39, whose lower end is secured to one arm of a bell-crank lever, 40, whose other arm is connected to a rod, 41, which in turn is connected to an arm, 42, of a butterfly or other valve, 43, located in and controlling the tailings discharged from the pipe, 13, in the bottom of the tank.

In the arrangement heretofore described and shown for illustrative purposes, the arms, 24, with their nozzles are supposed to be stationary while the shaft, 26, revolves and circular motion is given to the pulp, but it will be obvious that any other arrangement whereby there may be obtained a relative movement of the arms and hollow shaft, 26, will be but an equivalent of the construction before described and will be within the scope of my invention, it only being necessary that the parts shall be so arranged that during the rotation of one part relatively to the other the ports, 27, will register with the ports in the inner ends of the arm and the suction induced through the pipe, 29, and hollow shaft, 26, will result in the froth accumulating on the surface of the pulp being picked up by the nozzles and broken down and collapsed and drawn into the nozzles and through the arms and ports before mentioned into the hollow shaft, 26, and finally into the pipe, 29, and vacuum tank, 30. This action will be readily understood when it is suggested that under the ordinary conditions of operation, the bubbles are ruptured by the expansion of the contained air on reaching the surface or coming under the influence of the vacuum, where the external pressure is less than that within the bubbles.

The same result would be obtained as before suggested, by rotating the vacuum nozzles and their arms about the shaft, 26, in which case the vanes on the cone, 22, would not be necessary. If the arms, 24, were made to revolve, the vacuum nozzles would operate with a sweeping action over the surface of the bubbles and would pick up the bubbles in the same manner as before described, but the arrangement shown I regard as the preferred one.

It will also be understood that any desired number of arms and vacuum nozzles may be employed, although in the present instance but two are shown, one arranged diametrically opposite to the other.

Having thus described my invention what I claim as new and desire to secure by Letters Patent is:—

1. In apparatus of the character described, the combination of a tank adapted to contain a mineral-bearing pulp contain-

ing an oily agent having a preferential affinity for the mineral over the gangue constituent of the pulp; means for diffusing a gaseous fluid under pressure into the contents of the tank for agitating and aerating the same, said means permitting the passage of the gaseous fluid but not pulp and water, and pneumatic means for removing from the surface of the pulp, the froth, foam or suds forming thereon. 75

2. In apparatus of the character described, the combination of a tank adapted to contain a mineral-bearing pulp, having an oily agent with a preferential affinity for the mineral over the gangue constituent of the pulp; means for diffusing a gaseous fluid under pressure into the contents of the tank for agitating and aerating the same, said means permitting the passage of a gaseous fluid but not pulp and water, pneumatic 85 means for breaking down the froth, foam or suds forming on the surface of the pulp and simultaneously therewith removing the mineral particles carried by the froth; and means whereby the contents of the tank and 90 the pneumatic means are given rotary movement one relatively to the other.

3. In apparatus of the character described, the combination of a tank adapted to contain a mineral-bearing pulp having an oily agent with a preferential affinity for the mineral over the gangue constituent of the pulp; means for diffusing a gaseous fluid under pressure into the contents of the tank for agitating and aerating the same to 100 produce a froth, foam or suds composed of air bubbles to which the mineral particles attach, said means permitting the passage of the gaseous fluid but not pulp and water, and pneumatic means for exhausting the air 105 bubbles rising to the surface of the contents of the tank and simultaneously therewith liberating and separating the mineral particles.

4. In apparatus of the character described, the combination of a tank adapted to contain a mineral-bearing pulp having an oily agent with a preferential affinity for the mineral over the gangue constituent of the pulp; means for admitting a fluid under pressure into the contents of the tank for agitating and aerating the same to produce a froth, foam or suds composed of air bubbles to which the mineral particles attach; and pneumatic means for exhausting the air bubbles rising to the surface of the contents of the tank and thereby liberating and separating the mineral particles, said last-named means including a vacuum nozzle positioned in the path of the ascending air bubbles and 120 air-exhausting appliances connected to said nozzle. 125

5. In apparatus of the character described, the combination of a tank adapted to contain a mineral-bearing pulp having an oily 130

- agent with a preferential affinity for the mineral over the gangue constituent of the pulp; means for admitting a fluid under pressure into the contents of the tank for 5 agitating and aerating the same to produce a froth, foam or suds composed of air bubbles to which the mineral particles attach; pneumatic means for exhausting the air bubbles rising to the surface of the contents of the 10 tank and thereby liberating and separating the mineral particles, said last-named means including a vacuum nozzle positioned near the surface of the contents of the tank, and air-exhausting appliances connected to said 15 nozzle; and means for diverting the air bubbles into the range of action of the nozzle.
6. In apparatus of the character described, the combination of a tank adapted to contain a mineral-bearing pulp having an oily 20 agent with a preferential affinity for the mineral over the gangue constituent of the pulp; means for admitting a fluid under pressure into the contents of the tank for agitating and aerating the same to produce a froth, 25 foam or suds composed of air bubbles to which the mineral particles attach; pneumatic means for exhausting the air bubbles rising to the surface of the contents of the tank and thereby liberating and separating 30 the mineral particles, said last-named means including a vacuum nozzle positioned near the surface of the contents of the tank, and air exhausting appliances connected to said 35 nozzle; and a member positioned centrally of the tank having upwardly diverging sides for directing the ascending air bubbles into the range of action of the nozzle.
7. In apparatus of the character described, the combination of a tank adapted to contain 40 a mineral-bearing pulp having an oily agent with a preferential affinity for the mineral over the gangue constituent of the pulp; means for admitting a fluid under pressure into the contents of the tank for agitating and aerating the same to produce a froth, 45 foam or suds composed of air bubbles to which the mineral particles attach; pneumatic means for exhausting the air bubbles rising to the surface of the contents of the tank and thereby liberating and separating 50 the mineral particles, said last-named means including a vacuum nozzle positioned near the surface of the contents of the tank; air-exhausting appliances connected to said nozzle; and a cone-shaped member having upwardly diverging sides for directing the air-bubbles upwardly and outwardly into the 55 range of action of the nozzle.
8. In apparatus of the character described, the combination of a tank adapted to contain 60 a mineral-bearing pulp having an oily agent with a preferential affinity for the mineral over the gangue constituent of the pulp; means for admitting a fluid under pressure into the contents of the tank for 65 agitating and aerating the same to produce a froth, foam or suds composed of bubbles to which the mineral particles attach; pneumatic means for exhausting the air bubbles rising to the surface of the contents 70 of the tank thereby liberating and separating the mineral particles, said last-named means including a vacuum nozzle and air-exhausting elements connected thereto; and means whereby the nozzle and contents of 75 the tank are given a circular motion, one relatively to the other.
9. In apparatus of the character described, the combination of a tank adapted to contain a mineral-bearing pulp having an oily 80 agent with a preferential affinity for the mineral over the gangue constituent of the pulp; means for admitting a fluid under pressure into the contents of the tank for agitating and aerating the same to produce 85 a froth, foam or suds composed of air bubbles to which the mineral particles attach; pneumatic means for exhausting the air bubbles rising to the surface of the contents of the tank and thereby liberating and separating 90 the mineral particles, said last-named means including a vacuum nozzle positioned near the surface of the contents of the tank; air-exhausting appliances connected to said nozzle; and a member positioned centrally 95 of the tank having upwardly diverging sides for directing the ascending air bubbles into the range of action of the nozzle, said member having laterally extending vanes adapted to impart a circular motion to the contents of the tank.
10. In apparatus of the character described, the combination of a tank adapted to contain a mineral-bearing pulp having an oily 100 agent with a preferential affinity for the mineral over the gangue constituent of the pulp; means for admitting a fluid under pressure into the contents of the tank for agitating and aerating the same to produce a froth, foam or suds composed of air bubbles to which the mineral particles attach; pneumatic means for exhausting the air bubbles rising to the surface of the contents of the tank and thereby liberating and separating 105 the mineral particles, said last-named means including a vacuum nozzle positioned near the surface of the contents of the tank; air-exhausting appliances connected to said nozzle; a member positioned centrally of the tank having upwardly diverging sides for 110 directing the ascending air bubbles into the range of action of the nozzle, said member having laterally extending vanes adapted to impart a circular motion to the contents of the tank; and means for rotating the vanes.
11. In apparatus of the character described, the combination of a tank adapted to contain a mineral-bearing pulp having an oily 115 agent with a preferential affinity for the mineral over the gangue constituent of the pulp; means for admitting a fluid under pressure into the contents of the tank for agitating and aerating the same to produce a froth, foam or suds composed of bubbles to which the mineral particles attach; pneumatic means for exhausting the air bubbles rising to the surface of the contents of the tank and thereby liberating and separating 120 the mineral particles, said last-named means including a vacuum nozzle positioned near the surface of the contents of the tank; air-exhausting appliances connected to said nozzle; a member positioned centrally of the tank having upwardly diverging sides for directing the ascending air bubbles into the range of action of the nozzle, said member having laterally extending vanes adapted to 125 impart a circular motion to the contents of the tank; and means for rotating the vanes.
12. In apparatus of the character described, the combination of a tank adapted to contain a mineral-bearing pulp having an oily 130 agent with a preferential affinity for the mineral over the gangue constituent of the pulp; means for admitting a fluid under pressure into the contents of the tank for agitating and aerating the same to produce a froth, foam or suds composed of bubbles to which the mineral particles attach; pneumatic means for exhausting the air bubbles rising to the surface of the contents of the tank and thereby liberating and separating the mineral particles, said last-named means including a vacuum nozzle and air-exhausting elements connected thereto; and means whereby the nozzle and contents of the tank are given a circular motion, one relatively to the other.

the pulp, said tank having double walls forming an intervening space into which the pulp is first admitted, the innermost of said walls being shorter than the outer wall; a 5 chamber in the bottom of the tank having a porous upper surface forming a floor for the pulp-containing chamber; means for admitting a fluid under pressure into said chamber; said porous floor adapted to permit the passage of said fluid into the pulp 70 in innumerable fine streams distributed throughout the entire under surface of the pulp, whereby the pulp is agitated and aerated to produce a froth or foam which accumulates on its upper surface; a vacuum 75 nozzle positioned at the upper surface of the pulp and into the range of action of which the froth ascends and by which the air bubbles constituting the froth are broken down and the mineral particles liberated 80 and removed; a vacuum tank; pipe connections between said vacuum tank and said nozzle; said porous floor being declined from the inner circumference of the tank to the center of the tank; and a tailings 85 outlet connecting with the lowest point of said floor.

12. In apparatus of the character described, the combination of a tank adapted to contain a mineral-bearing pulp having an oily agent with a preferential affinity for the mineral over the gangue constituent of the pulp, said tank having double walls 30 forming an intervening space into which the pulp is first admitted, the innermost of said walls being shorter than the outer wall; a chamber in the bottom of the tank having a porous upper surface forming a floor for the pulp-containing chamber; means for admitting a fluid under pressure into said chamber; said porous floor adapted to permit the passage of said fluid into the pulp 35 in innumerable fine streams distributed throughout the entire under surface of the pulp, whereby the pulp is agitated and aerated to produce a froth or foam, which accumulates on its upper surface; a vacuum nozzle positioned at the upper surface of the 40 pulp and into the range of action of which the froth ascends and by which the air bubbles constituting the froth are broken down and the mineral particles liberated and removed; a vacuum tank; pipe connections 45 between said vacuum tank and said nozzle; means for dividing the fluid-chamber in the bottom of the tank into compartments; and a fluid-supply pipe having independently controlled branches connecting with each of 50 said compartments.

13. In apparatus of the character described, the combination of a tank adapted to contain a mineral-bearing pulp having an oily agent with a preferential affinity for 55 the mineral over the gangue constituent of the pulp, said tank having double walls forming an intervening space into which the pulp is first admitted, the innermost of said walls being shorter than the outer wall; a 60 chamber in the bottom of the tank having a

porous upper surface forming a floor for the pulp-containing chamber; means for admitting a fluid under pressure into said chamber; said porous floor adapted to permit the passage of said fluid into the pulp 70 in innumerable fine streams distributed throughout the entire under surface of the pulp, whereby the pulp is agitated and aerated to produce a froth or foam which accumulates on its upper surface; a vacuum 75 nozzle positioned at the upper surface of the pulp and into the range of action of which the froth ascends and by which the air bubbles constituting the froth are broken down and the mineral particles liberated 80 and removed; a vacuum tank; pipe connections between said vacuum tank and said nozzle; said porous floor being declined from the inner circumference of the tank to the center of the tank; and a tailings 85 outlet connecting with the lowest point of said floor.

14. In apparatus of the character described, the combination of a tank adapted to contain a mineral-bearing pulp having 90 an oily agent with a preferential affinity for the mineral over the gangue constituent of the pulp, said tank having double walls forming an intervening space into which the pulp is first admitted, the innermost of 95 said walls being shorter than the outer wall; a chamber in the bottom of the tank having a porous upper surface forming a floor for the pulp-containing chamber; means for admitting a fluid under pressure into said 100 chamber; said porous floor adapted to permit the passage of said fluid into the pulp in innumerable fine streams distributed throughout the entire under surface of the pulp, whereby the pulp is agitated and aerated to produce a froth or foam which accumulates on its upper surface; a vacuum 105 nozzle positioned at the upper surface of the pulp and into the range of action of which the froth ascends and by which the air bubbles constituting the froth are broken down and the mineral particles liberated and removed; a vacuum tank; pipe connections between said vacuum tank and said nozzle; said porous floor being declined from the 110 inner circumference of the tank to the center of the tank; a tailings outlet connecting with the lowest point of said floor; a valve in the tailings outlet; and means controlled by the level of the pulp in the tank for operating said valve.

15. In apparatus of the character described, the combination of a tank adapted to contain a mineral-bearing pulp having an oily agent with a preferential affinity for the 125 mineral over the gangue constituent of the pulp, said tank having double walls forming an intervening space into which the pulp is first admitted, the innermost of said walls being shorter than the outer wall; a chamber 130

- in the bottom of the tank having a porous upper surface forming a floor for the pulp-containing chamber; means for admitting a fluid under pressure into said chamber; said 5 porous floor adapted to permit the passage of said fluid into the pulp in innumerable fine streams distributed throughout the entire under surface of the pulp, whereby the pulp is agitated and aerated to produce a 10 froth or foam which accumulates on its upper surface; a vacuum nozzle positioned at the upper surface of the pulp and into the range of action of which the froth ascends and by which the air bubbles constituting the 15 froth are broken down and the mineral particles liberated and removed; a vacuum tank; pipe connections between said vacuum tank and said nozzle; and a shaft journaled vertically in the tank having means for imparting circular motion to the contents of 20 said tank.
16. In apparatus of the character described, the combination of a tank adapted to contain a mineral-bearing pulp having an oily agent with a preferential affinity for the 25 mineral over the gangue constituent of the pulp, said tank having double walls forming an intervening space into which the pulp is first admitted, the innermost of said walls 30 being shorter than the outer wall; a chamber in the bottom of the tank having a porous upper surface forming a floor for the pulp-containing chamber; means for admitting a fluid under pressure into said chamber; said 35 porous floor adapted to permit the passage of said fluid into the pulp in innumerable fine streams distributed throughout the entire under surface of the pulp, whereby the pulp is agitated and aerated to produce a 40 froth or foam, which accumulates on its upper surface; a vacuum nozzle positioned at the upper surface of the pulp and into the range of action of which the froth ascends and by which the air bubbles constituting the 45 froth are broken down and the mineral particles liberated and removed; a vacuum tank; pipe connections between said vacuum tank and said nozzle; a shaft journaled vertically in the tank; and arms carried by the 50 shaft substantially parallel with and adjacent said floor and adapted to operate with a sweeping movement thereover.
17. In apparatus of the character described, the combination with a tank adapted 55 to contain a mineral-bearing pulp having an oily agent with a preferential affinity for the mineral over the gangue constituent of the pulp; means for admitting a fluid under pressure into the contents of the pulp for 60 agitating and aerating the same to produce a froth, foam or suds composed of a mass of air bubbles, to which the mineral particles attach; a rotatable shaft having vanes operating in the pulp for imparting circular motion thereto; vacuum nozzles positioned 65 above the upper surface of the pulp and into the range of action of which the froth, foam or suds ascends, each of said nozzles having a hollow arm, and said pipe being hollow having ports adapted to register with the inner 70 ends of said arms; a vacuum tank; and pipe connections between said vacuum tank and said hollow shaft.
18. In an apparatus for separating the metalliferous from the non-metalliferous ingredients of an ore mass, the combination 75 of a pulp receptacle, means for forming substantially uniformly distributed bubbles of air at the bottom of the said receptacle, means remote from the axial center of the 80 receptacle for introducing ore pulp and projecting along radial lines to be distributed substantially uniformly over the peripheral parts of the cross area of the receptacle, the said pulp being acted upon by the said bubbles to remove the metalliferous ingredients therefrom, and means for discharging from the receptacle the barren pulp which has been acted upon by the bubbles.
19. In an apparatus for separating the 90 metalliferous from the non-metalliferous ingredients of an ore mass, the combination of a pulp receptacle, means for forming substantially uniformly distributed bubbles of air at the bottom of the said receptacle, 95 means for introducing ore pulp at points distributed along the periphery of the receptacle and projecting the said ore inward along radial lines to be distributed substantially uniformly over the peripheral parts 100 of the cross area of the receptacle, the said pulp being acted upon by the said bubbles to remove the metalliferous ingredients therefrom, and means for discharging from the receptacle the barren pulp which has 105 been acted upon by the bubbles.
20. In an apparatus for separating the metalliferous from the non-metalliferous ingredients of an ore mass, the combination 110 of a pulp receptacle, a porous bottom for the receptacle inclined downward along lines extending from the periphery to the center thereof, means for supplying air under pressure below the said porous bottom and forcing it therethrough to form relatively large substantially uniformly distributed air bubbles, means for supplying ore pulp to the receptacle at points distributed along the periphery of the receptacle and closely adjacent the said porous bottom, the 115 said pulp flowing downward and inward over the said bottom in the directions of inclination and being acted upon by the said bubbles to receive the metalliferous ingredients therefrom, and means at the center of the bottom for collecting and discharging the resulting barren pulp from the receptacle at the center of the bottom.
21. In an apparatus for separating the metalliferous from the non-metalliferous in- 130

2. In an apparatus for separating the metalliferous from the non-metalliferous ingredients of an ore mass, the combination of a pulp receptacle, a porous bottom for the receptacle inclined along lines extending radially from the center thereof, means for supplying air under pressure below the said porous bottom and forcing it therethrough to form relatively large air bubbles, means for changing the action of the air at one annular portion of the bottom relatively to the action at another annular portion, means for supplying ore pulp to the receptacle at points closely adjacent the upper parts of the said porous bottom, the said pulp flowing over the said bottom in the direction of inclination and being acted upon by the said bubbles to remove the metalliferous ingredients therefrom, and means for collecting and discharging from the receptacle the resulting barren pulp which reaches the lower parts of the bottom.
22. In an apparatus for separating the metalliferous from the non-metalliferous ingredients of an ore mass, the combination of a pulp receptacle, a porous bottom for the receptacle inclined downward along lines extending from the periphery to the center thereof, means for supplying air under pressure below the said porous bottom and forcing it therethrough to form relatively large air bubbles, means for changing the action of the air at one annular portion of the bottom relatively to the action at another annular portion, means for supplying ore pulp to the receptacle at points distributed along the periphery closely adjacent the said porous bottom, the said ore flowing downward and inward over the said bottom in the directions of inclination and being acted upon by the said bubbles to remove the metalliferous ingredients therefrom, and means at the center of the bottom for collecting and discharging the resulting barren pulp from the receptacle.
23. In apparatus for separating the metalliferous from the non-metalliferous ingredients of an ore mass, the combination of a pulp receptacle, means for forming substantially uniformly distributed bubbles within the tank, and means for exhausting the bubbles from the upper surface of the pulp.
24. In apparatus for separating the metalliferous from the non-metalliferous ingredients of an ore mass, the combination of a pulp receptacle, means for agitating and aerating the pulp to form a froth, and pneumatic means for breaking down the froth and simultaneously carrying off the mineral particles floated thereby.
25. In apparatus for separating the metalliferous from the non-metalliferous ingredients of an ore mass, the combination of a pulp receptacle, means for agitating and aerating the pulp to form a froth, and pneumatic means for breaking down the froth and simultaneously carrying off the mineral particles floated thereby, and means whereby the contents of the tank and the pneumatic means will give rotary movement one relatively to the other.
26. In apparatus for separating the metalliferous from the non-metalliferous ingredients of an ore mass, the combination of a pulp receptacle, means for agitating and aerating the pulp to form a froth, and pneumatic means for breaking down the froth and simultaneously carrying off the mineral particles floated thereby, and a closed receiver for said mineral particles.
27. The herein described process for separating the metalliferous from the non-metalliferous particles of an ore mass, which consists in forming a cylindrical body of liquid pulp of the ore having a relatively large diameter, forming bubbles of air at the bottom of the body and permitting them to rise therethrough and adhere to and remove the metalliferous particles, and projecting fresh pulp at relatively low pressure into the said pulp body in sheets directed radially transversely across the vertical lines of movement of the bubbles and commencing at points distributed along the periphery of the pulp body.
28. In an apparatus for separating the metalliferous from the non-metalliferous ingredients of an ore mass, the combination of a cylindrical pulp receptacle, means for forming substantially uniformly distributed bubbles of air at the bottom of the said receptacle, means remote from the axial center of the receptacle for introducing ore pulp and projecting it horizontally to be distributed substantially uniformly over the cross area of the receptacle, the said pulp being acted upon by the said bubbles to remove the metalliferous ingredients therefrom, and axially arranged means for discharging from the receptacle the barren pulp which has been acted upon by the bubbles.

In testimony whereof I affix my signature in presence of two witnesses.

JOHN M. CALLOW.

Witnesses:

ERNEST GAYFORD,
H. A. MERCER.
